ATHELSTAN E. GOOCH, OF BROCKTON, MASSACHUSETTS.

ACTUATING MEANS FOR FUEL-Injector PLUNGERS.

1,390,541.

Specification of Letters Patent. Patented Sept. 13, 1921.

Application filed June 20, 1917. Serial No. 175,850.

To all whom it may concern:

Be it known that I, RICHARD H. RANDALL, a citizen of the United States, residing at Brockton, in the county of Plymouth and 5 State of Massachusetts, have invented certain new and useful Improvements in Actuating Means for Fuel-Injector Plungers; and I do hereby declare the following to be a full, clear, and exact description of the invention, 10 such as will enable others skilled in the art to which it appertains to make and use the same.

This invention relates to improvements in actuating means for the plunger of a valve 15 for injecting fuel charges into the cylinder of an internal combustion engine, and its primary object is the provision of novel means of this type which shall be capable of adjustment to enable the size of the fuel 20 charges injected into the cylinder of the engine to be varied and controlled at will.

With the above and other objects in view, the invention consists in the construction, combination and arrangement of parts hereinafter fully described and claimed, and 25 illustrated in the accompanying drawings, wherein:

Figure 1 is a view in elevation of a two-cycle Diesel engine equipped with a valve 30 actuating means constructed in accordance with my invention.

Fig. 2 is a longitudinal sectional view of the valve.

Fig. 3 is an elevation of the cam of the 35 valve actuating means, and

Fig. 4 is a longitudinal sectional view of the cam.

Referring to the drawings by reference numerals, 1 designates an internal combustion engine of that type known as the Diesel engine. The engine is equipped with an injector valve which comprises a casing 19 and a plunger 20 operating in a longitudinal bore or passage 21 having a reduced outlet 22 and 40 an enlarged outer portion 23, or counter bore, for the reception of a coiled spring 24. The coiled spring 24 is disposed on the plunger 20 and interposed between the shoulders or lugs 25 and an adjustable set collar 26 which 45 is adapted to vary the tension of the spring. The valve casing is also provided with a fuel inlet passage 27 connected with the passage 21 by a reduced branch passage 28 at a 50 point adjacent to the reduced outlet 22. The

valve casing receives a threaded portion 29 of a supply pipe 30.

The plunger of the injector valve is engaged by the inner end of a rocker arm or lever 31 pivoted at an intermediate point at 32 and having its inner end bearing against 60 the outer end of the plunger. The outer portion of the rocker arm or lever is provided with a slot 33 and is adjustably connected with the upper end of a link rod 34 having a pivot 35 operating in the slot and adapted to 65 be secured at different points along the rocker arm to vary the stroke of the same and the consequent stroke of the plunger. By this construction, the amount of oil or 70 other fuel injected into the cylinder may be varied and controlled by changing the stroke of the plunger through the adjustment of the link to the rocker arm.

The link 34 is pivoted at 36 to a reciprocating cam actuated member 37, consisting of 75 a rod operating in a guide 39 and having a rounded lower end 40 which is engaged by a cam 41. The cam 41, as clearly illustrated in Fig. 4 of the drawings, consists of a tapered or conical sleeve slidably interlocked 80 with a shaft 42 by a key 43 and provided with a longitudinal groove or cam portion 44 adapted to receive the end 40 of the reciprocating member for permitting the plunger to move outwardly to open the valve 85 while withdrawing the plunger from the branch passage 28. The cam which is provided with an annular groove 45 for the reception of the fork 46 of an operating actuating lever 47, is adapted by its longitudinal 90 adjustment to vary the stroke of the plunger, and the concentric portion of the tapered sleeve is adapted to maintain the plunger in its closed position. Instead of providing a tapered cam, a stepped construction of cam 95 may be used as will be readily understood. During a portion of each revolution of the cam the end 40 of the reciprocating rod or member 37 will move into the longitudinal groove 44 thereby causing spring of the 100 plunger to actuate the latter and open the injector valve, and as the conical cam tapers in circumference, the longitudinal groove 44 will be correspondingly tapered and the degree of the opening and closing movements 105 of the plunger will vary with the position of the cam.

The shaft 42 is driven from the crank shaft

49 of the engine, and any suitable means, not shown, may be employed for establishing a driving connection between these shafts. The inward movement of the reciprocatory member 37 is limited by a nut 54 mounted on a threaded portion 55 of the reciprocatory member 37. The guide 39 is of tubular form, as shown, but the same may of course be varied in construction.

10. What is claimed is:

1. Actuating means for the plunger of a valve for injecting fuel charges into the cylinder of an internal combustion engine, comprising a rocker arm engaging the plunger and adapted to move the plunger inwardly, a retraction spring adapted to move the plunger outwardly, a link rod, means pivoting the link rod to the rocker arm and adapted to be adjusted lengthwise of the rocker arm in the direction of and away from its pivot, and means for imparting motion to the link rod.
2. Actuating means for the plunger of a valve for injecting fuel charges into the cylinder of an internal combustion engine, comprising a rocker arm adapted to move the plunger inwardly, a retraction spring adapted to move the plunger outwardly, an engine actuated reciprocatory member, a link rod pivoted to the reciprocatory member, and means pivoting the link rod to the rocker arm and adapted to be adjusted lengthwise of the rocker arm in the direction of and away from its pivot.
3. Actuating means for the plunger of a valve for injecting fuel charges into the cylinder of an internal combustion engine, comprising a rocker arm adapted when ac-

tuated to move the plunger inwardly, a retraction spring adapted to move the plunger outwardly, a reciprocatory member, a link rod pivotally connected to the rocker arm and pivotally connected with the reciprocatory member, a driven shaft, and a conical sleeve mounted upon said shaft for adjustment with respect to said reciprocatory member, said sleeve being provided with a longitudinal groove having a bottom wall parallel with the axis of the shaft and adapted to receive the adjacent end of said reciprocatory member once during each rotation of the sleeve.

4. Actuating means for the plunger of a valve for injecting fuel charges into the cylinder of an internal combustion engine, comprising a rocker arm adapted to move the plunger inwardly, a retraction spring adapted to move the plunger outwardly, a reciprocatory member, a link rod pivotally connected to the rocker arm adjustably and pivotally connected with the reciprocatory member, a driven shaft and a conical sleeve mounted upon said shaft for adjustment with respect to said reciprocatory member, said sleeve being provided with a longitudinal groove having a bottom wall parallel with the axis of the shaft and adapted to receive the adjacent end of said reciprocatory member once during each rotation of the sleeve.

In testimony whereof I affix my signature in presence of two witnesses.

RICHARD H. RANDALL.
